CLAIM

The ornamental design for a configurable organizer system for handbag, as shown and described.

DESCRIPTION

FIG. 1 is a perspective view of a configurable organizer system for handbag, showing my design.

FIG. 2 is front view thereof.

FIG. 3 is a right-side view thereof; and,

FIG. 4 is a bottom view thereof.

The broken lines shown in the drawings depict magnetic connectors and stitching, and form no part of the claimed design.
